UNITED STATES PATENT OFFICE.

LOUIS A. MAXSON, OF CLAREMONT, NEW HAMPSHIRE, ASSIGNOR TO SULLIVAN MACHINERY COMPANY, A CORPORATION OF MASSACHUSETTS.

PERCUSSIVE MOTOR.

Application filed January 2, 1920. Serial No. 349,013.

My invention relates to percussive motors. Its object is to provide an improved percussive motor. A further object of my invention is to provide an improved motor in which the supply of fluid for a stroke in either direction is more expeditiously delivered than in motors heretofore constructed, and in which, simultaneously, I have avoided the production of excessive cushioning pressures by delaying admission of a large part of the charge of motive fluid until substantially the beginning of the stroke in either direction. Another object is to so combine the features of valved and valveless motors as to obtain freedom from the excessive preadmission found in valveless tools while using features of valveless construction to secure just the desired degree of cushion, and to increase the capacity of the motor above the limits imposed by the relation of admission to cushion in valveless tools and by port size in valved tools. A further object of my invention is to admit and store up fluid pressure for use in the cylinder during the period at about the middle of the traverse of the piston in either direction when flow through the inlet port is reduced to much less than at other times in valveless tools. Other objects of my invention will be apparent from the following specification and the appended claims.

In the accompanying drawings, I have shown, for purposes of illustration, three forms which my invention may assume in practice.

In these drawings—

Fig. 1 represents a developed section on the broken line 1—1 of Fig. 2, certain parts of the motor not constituting per se a part of my invention, being shown in elevation.

Fig. 2 is a section on line 2—2 of Fig. 1.

Figs. 3 and 4 are partial sectional views showing modified embodiments.

In these drawings I have shown a percussive motor having a cylinder member indicated generally by 1, which is closed at opposite ends by heads 2 and 3 to which are respectively attached a chuck housing 4 and a throttle valve 5. The cylinder is provided with a bore of uniform diameter 6, and within the cylinder reciprocates a piston 7 having heads of like length 8 and 9, and between these heads is provided a reduced portion 10. Around this reduced portion 10 is an annular space 11 which is adapted to cooperate with suitable ports, hereinafter described, in the

fluid distribution to the cylinder. Extending longitudinally within the walls of the cylinder are inlet passages 13, to which fluid is supplied from any suitable source under control of the throttle valve 5. The inlet passages 13 are provided with ports 14 opening directly into the cylinder midway of its length, the length of the groove in the piston being sufficient to leave the inlet port full open in either extreme position of the piston. Cooperating with this inlet port are fluid supply passages 15 and 16, which open into the cylinder on opposite sides of the inlet port by means of ports 17 and 18, these ports being separated by such distance that either ports 17 or ports 18 are always at least in partial communication with the inlet ports 14, and passages 15 and 16 open into the opposite ends of the cylinder through ports 19 and 20, respectively. The construction so far described is well known save for the somewhat smaller size of the passages 15 and 16.

Cooperating with the inlet port and distribution passages described hereabove, I have arranged a port 22 at the opposite side of the cylinder, and cooperating with this port is a valve 23 adapted to control the supply and the distribution to the cylinder from two series of storage chambers 25 and 26, the separate chambers of which communicate 85 with each other by passages 25' and 26'. The valve which I have illustrated is of the four-spool type, the spools being indicated, respectively, by 27, 28, 29, and 30. The valve is mounted in a valve cylinder 32 of 90 such length that the port formed between the spools 28 and 29 always communicates with the port 22 and alternately with the sets of ports 33 and 34 communicating with the storage chambers 25, 26. Arranged at the outside 95 of the ports 33, 34, are a pair of passages 37 and 38 opening into the opposite ends of the cylinder by means of ports 39 and 40 and opening into the valve chamber adjacent the ports 33, 34 by means of ports 41 and 42.

It will be understood that the proportioning of the sizes of various parts will be such as to, in practice, best effect the desired results, but I have herein shown the valve as of a relatively large size for purposes of clarity of illustration.

To effect the throwing of the valve 23, I have provided at the ends of the valve chamber 32, ports 43 and 44 opening into the bore of the cylinder in such position as to be 110

uncovered by the inner faces of the piston heads slightly before the piston reaches the end of its strokes and immediately before the exhaust ports (hereafter described) are opened. These ports communicate with the extreme ends of the valve chambers 32 by passages 47 and 48, and communicating with these passages are further ports 45 and 46 so located as to be cleared by the outer ends of the piston slightly before the instant when the main motor exhaust ports 51 and 52 are opened, whereby the ends of the valve chamber may be alternately connected first with the cylinder wherein a reduced pressure exists as the result of expansion of the motive fluid, and then immediately afterward communicate with the exhaust ports 51 or 52, the latter being located in such position as to be fully open at the end of the piston strokes. The operation is such that when the port 45 or port 46 is first uncovered by the piston, the valve 23 is started towards its other position due to the action of live fluid through the port 44 or 43 on one end and expanded fluid on the other, and the throw is completed when the exhaust port 51 or 52 is opened. What is accomplished here is the closure of communication between the expansion chambers and the ends of the cylinder before the latter are opened to exhaust. This prevents the loss of the fluid which has not been fully expanded in the storage chambers.

The operation of the form of my invention disclosed for purposes of illustration in Figs. 1 and 2 is as follows: Fluid pressure is admitted through the inlet passage 13, enters the cylinder through the port 14, and is conducted to the right hand or forward end of the cylinder in Fig. 1. Fluid simultaneously passes through the port 43 and into the valve chamber 32 at the right hand end thereof and holds the valve 23 in the position shown in Fig. 1. As no fluid has previously been stored in the storage chamber 25, the admission through the passage 15 will cause the piston to start to the left. Fluid is likewise simultaneously passing through the port 22, through the space between the heads 28 and 29 in the spool valve, and into the storage chambers 26, which will accordingly be filled with fluid under pressure. When the piston overruns the port 18, fluid will begin to pass through the passage 16 into the left hand end of the cylinder, but a sufficient pressure to check the piston will not build up therein until about the completion of the stroke. It will here be noted that fluid entering either end of the cylinder immediately after the ports 17 or 18 are opened, will have its cushioning effect minimized by the volume of the passages 37 or 38 which communicate with the end of the cylinder. When the port 45 is uncovered by the right hand end of the piston, the pressure in the right end of the chamber 32 will drop as this chamber then

communicates with the right hand end of the cylinder wherein expansion has reduced the pressure to a certain extent. The valve 23 will thus start to move over and will close communication between the ports 33 and 41 before the port 51 is opened, it being noted that the port 44 is so located as to be uncovered before the exhaust port 51 is opened. This will serve to save unexpanded fluid in the storage chambers during normal operation of the motor. During this first stroke, of course, the chamber 25 contained only such pressure as passed to it through the passage 15. The throw of the valve is completed by the end of the piston stroke. Upon the throwing of the valve 23 and the connection, by the passage between the heads 27 and 28 of the valve 23, of the storage chambers 26 with the passage 38, the large charge of stored fluid will be at once connected with the end of the cylinder and aid in causing a forward stroke of great speed and force due to the large volume of pressure fluid conducted to the cylinder. As the piston moves to the right upon this stroke, fluid will again be admitted through the passage 15 to the right hand end of the cylinder when the port 17 is uncovered by the piston, this pressure, however, not building up a sufficient pressure in the cylinder to unduly cushion the blow. When the piston nearly reaches the end of its travel in the right hand direction, the ports 46 and 43 will be opened and the valve 23 shifted by the difference in pressures on its ends, and the exhaust port 52 will also be overrun. The fluid stored in the chamber 25 during the forward stroke will then pass to the cylinder. It will be obvious that means is provided in this motor whereby fluid may be stored for use to effect a stroke in either direction during the substantially entire previous stroke in the opposite direction, and whereby a large quantity of motive fluid may be admitted to the cylinder at the desired instant, i. e., at the beginning of a stroke, to effect quick movement of the piston. Another beneficial result is that while a motor which is positive in starting from any position is provided, it has not been necessary to so proportion the several parts that an excessive pre-admission will occur. A further advantage lies in the fact that by the throwing of the valve 23, as described, the partially expanded fluid contained in the storage chambers is not lost when the exhaust ports 120 open, but is preserved, by the cutting off of the storage chambers from communication with the cylinder prior to the opening of the exhaust ports, for use when supplemented on a later stroke.

It will be further noted that I have illustrated, although they need not be used, valves 61 and 62 whereby, if desired, the passages 15 and 16 may be closed after the motor has started and is in operation, the entire opera-

tion being controlled by the valve 23, in which case cushioning will be reduced to a minimum. It will be obvious, further, that either of the valves may be partially closed while the other remains open, thereby adjusting cushioning at either end as may be desired. For example, by entirely closing the valve 61, it will be possible to cause the striking of an almost entirely uncushioned blow, but by leaving the valve 62 open a cushion may be maintained at the rear end of the cylinder. It will be understood, however, that the provision of the valves 61 and 62 is no wise essential.

In Fig. 3 I have shown another modification which may be given to the ports 15 and 16, these ports being considerably enlarged between their ends to form expansion chambers 71 and 72 to thereby delay building up of pressure in the ends of the cylinders and to provide a storage reservoir from which a greater charge of fluid may be admitted to perform the stroke. In this case, the ports 17 and 18, and 19 and 20 may be materially enlarged and a very powerful action obtained.

In Fig. 4 I have shown a still further modification which this invention may assume in practice. In this form the passages 15 and 16 are provided of much greater size than in the form shown in Fig. 1, and the ports 17' and 18' are removed from the inlet port a greater distance, in such a manner that they are not opened by the piston until a considerable portion of the stroke in either direction has been completed. In order to render the motor automatically starting in any position, what may be termed starting ports 81 and 82 are provided opening into the cylinder in such position that one or the other is at least partially open in any position of the piston. These ports are connected with the ports 15 and 16, and accordingly fluid admitted through them will be conducted to the ports 15 and 16 and enable the starting of the motor. When the motor gets up to speed, however, the area of these ports is so small that they do not substantially influence the speed of the tool.

While I have in this application specifically described three embodiments which my invention may assume in practice, it will be understood that the same are shown for purposes of illustration only, and that the invention may be modified and embodied in various other forms without departing from its spirit or the scope of the appended claims.

What I claim as new and desire to secure by Letters Patent is:

1. In a fluid pressure percussive motor, a cylinder, a piston therein, fluid distribution means comprising an inlet port, fluid storage means, means whereby fluid to be used at one end of said cylinder is admitted through said inlet port to said storage means during substantially an entire stroke towards that end

and whereby said fluid storage means is then placed in communication with said end of the cylinder, and means whereby fluid is admitted through said inlet port and conducted to the other end of the cylinder simultaneously with the admitting of fluid for the first mentioned end.

2. In a fluid pressure percussive motor, a cylinder, a piston therein, and means for supplying fluid to effect movement of said piston in said cylinder comprising an inlet port, passages controlled by said piston to conduct fluid pressure to the ends of said cylinder, and supplemental fluid pressure supply means for each end of said cylinder connectible each 75 with its respective end of the cylinder and placed in communication with said inlet port prior to the opening of said piston controlled passages.

3. In a fluid pressure percussive motor, a cylinder, a piston therein, fluid supply, exhaust, and distribution means for said cylinder, said fluid distribution means comprising a storage chamber communicable with one end of said cylinder, and means to interrupt 80 said communication prior to the opening of the exhaust from that end of said cylinder.

4. In a fluid pressure percussive motor, a cylinder, a piston therein, an inlet port fluid distribution ports controlled by said piston 95 for the supply of fluid pressure to the ends of the cylinder, and means to supplement the supply of fluid pressure thereto comprising fluid storage means and means for supplying the same with fluid pressure wide open at a time when the supply to said distribution ports is at a minimum.

5. In a fluid pressure percussive motor, a cylinder, a piston therein having a pair of heads separated by an annular groove, an inlet port opening into said cylinder adjacent the center thereof, a port opposite said inlet port, a storage chamber communicable with said cylinder by means of said opposite port, and means for charging said storage chamber 100 during one pass of the piston, discontinuing charging at the end of said pass, and discharging it to the end of said cylinder on the next successive pass.

6. In a fluid pressure percussive motor, a cylinder, a piston therein, an inlet port, a pair of fluid pressure storage chambers communicable respectively with the opposite ends of the cylinder, and means including means for interrupting communication between said chambers and the ends of said cylinder whereby said storage chambers are charged with fluid pressure on alternate passes of the piston, and connected with opposite ends of the cylinder during the intervals between chargings.

7. In a fluid pressure percussive motor, a cylinder, a piston therein, an inlet port and fluid distribution means cooperating therewith, additional fluid distribution means com- 120

prising storage chambers, and a valve cooperating therewith whereby fluid to be used at one end of said cylinder is admitted through said inlet port to one of said storage chambers during the interval when supply to the same end of the cylinder through said first mentioned fluid distribution means is at a minimum.

8. In a fluid pressure percussive motor, a cylinder, a piston therein, an inlet port, fluid distribution passages controlled by said piston, and means for supplementing the fluid supply through said piston controlled passages including a storage chamber adapted to be brought into communication with an end of the cylinder at the instant the piston reaches that end.

9. In a fluid pressure percussive motor, a cylinder, a piston therein, an inlet port, passages controlled by said piston to conduct fluid pressure to the ends of said cylinder, a supplemental fluid distribution system including a pair of storage chambers, a valve controlling the communication of the same with the fluid pressure supply and with the opposite ends of the cylinder, and means for throwing said valve controlled by said piston.

10. In a fluid pressure percussive motor, a cylinder, a piston therein, an inlet port, fluid distribution means controlled by said piston to conduct fluid pressure to the ends of said cylinder, and supplemental fluid pressure supply means controlled by said piston whose communication with said ends of said cylinder is opened and closed subsequent respectively to the opening and closing of said first mentioned piston controlled means.

11. In a fluid pressure percussive motor, a cylinder, a piston therein, a fluid distribution system controlled by said piston, and a supplemental fluid distribution system comprising a pair of fluid storage chambers communicable each with one end of said cylinder and closed thereto prior to the opening of an exhaust from its respective end of said cylinder.

12. In a fluid pressure percussive motor, a cylinder, a piston having a pair of heads separated by an annular groove, an inlet port,

fluid distribution ports adapted to be connected in alternation with said inlet port by said groove and leading to opposite ends of said cylinder, a port circumferentially spaced from said inlet port but in the same transverse plane, a pair of storage chambers, a pair of passages communicating with the ends of said cylinder, and a piston controlled valve adapted to connect said storage chambers alternately with said second mentioned port and with said passages.

13. In a fluid pressure percussive motor, a cylinder, a piston therein, said cylinder having a valve controlled fluid pressure distribution system and piston controlled exhaust ports, and a supplemental distribution system comprising passages adapted to be connected in alternation to said fluid pressure supply and leading to the ends of said cylinder, and means to adjust the flow through said passages comprising valves located therein.

14. In a fluid pressure percussive motor, a cylinder, a piston, a piston controlled distributing valve adapted to effect admission to the opposite ends of said cylinder at the extreme end of alternate strokes of the piston, a supplemental fluid distributing system comprising an inlet port and piston controlled bypass ports leading to the opposite ends of said cylinder, and means to vary the cushion produced by fluid passing through these ports including a valve located between the ends of each of them.

15. In a fluid pressure percussive motor, a cylinder, a piston therein, an inlet port, a fluid pressure distribution system controlling the supply of fluid to opposite ends of said cylinder at the instant when the piston reaches said ends, a supplemental distribution system comprising means for admitting fluid pressure to the ends of said cylinder prior to the moment when said piston reaches said ends, and means to minimize the cushioning action occasioned by such pre-admission including valves controlling said supplemental means.

In testimony whereof I affix my signature.
LOUIS A. MAXSON.
